UNITED STATES PATENT OFFICE.

WILEY T. CARTER, OF HENDERSON, NORTH CAROLINA.

MOP-HOLDER.

1,106,362.

Specification of Letters Patent. Patented Aug. 11, 1914.

Application filed May 22, 1914. Serial No. 840,325.

To all whom it may concern:

Be it known that I, WILEY T. CARTER, a citizen of the United States of America, and resident of Henderson, in the county of Vance and State of North Carolina, have invented certain new and useful Improvements in Mop-Holders, of which the following is a specification.

This invention relates to mops and particularly to means for holding a cloth for manipulating the same as in washing dishes, scrubbing or in fact performing any other cleaning operations of a domestic character.

An object of this invention is to provide a handle or handles provided with clamping or cloth-holding jaws or means, so that cloths may be readily applied to or removed from the holding device, means being provided whereby the said cloth is clamped and effectually retained in the holder.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a perspective view of cloth holding jaws in assembled relation, the same being open for the admission or application of cloth; Fig. 2 illustrates a plan view of the device in open position; Fig. 3 illustrates an edge view of the device shown in Fig. 1; and Fig. 4 illustrates a fragment 40 of the clamping device showing the clamping jaws in position to hold the cloth.

In these drawings 5 denotes one of the handles comprising a length of material bent on itself to form a loop 6 constituting one extremity of the handle, the ends of the length of material being shaped to form eyes 7 and 8 which constitute bearings for the other clamping member, which last mentioned clamping member constitutes the handle 9 formed of a length of material bent on itself to produce an outer loop 10 which constitutes the end of the handle. The material constituting the handle 9 has curved

portions 11 and 12 which pass through the eyes 7 and 8 and the handle is rotatable or pivotally mounted with respect to the other handle or clamping member. The material constituting the handle 9 is continued past the eyes 7 and 8 and is wrapped or twisted as at 13, the extremities of the material being of curved formation and constituting tangs 14 and 15 which penetrate or embed themselves into the cloth to such an extent as to form an anchorage for the said cloth. The handles or clamping members 5 and 9 also serve to hold the cloth in place, thus augmenting the action of the tangs to such an extent as to prevent dislodgment of the cloth.

As a means for holding the handles or clamps 5 and 9 in approximately parallel relation to each other, which is the position they occupy or assume when the cloth is clamped between them, a loop or retainer 16 is slidably applied to the handle 5 and the said loop or retainer is of such shape and construction as to receive the other handle 9 and retain the clamping members against movement so long as the loop is applied to them.

I claim—

In a mop holder, a handle comprising a length of material bent on itself to form a loop constituting the outer extremity of the handle, the ends of the said length of material having eyes, a handle comprising a length of material bent on itself to form a loop constituting the outer extremity of the handle and having portions extending through the eyes of the first mentioned handle and pivotally mounted therein, the material constituting the second mentioned handle being twisted on itself to retain the two lengths in proper relation to the eyes of the first mentioned handle and the extremities of the said length of material of the second mentioned handle being diverged and constituting cloth engaging tangs, and means for retaining the handles in position to clamp a cloth therebetween.

In testimony whereof, I affix my signature in the presence of two witnesses.

WILEY T. CARTER.
